PYROPHORIC LIGHTING MECHANISM

Louis V. Aronson, Newark, N. J., assignor to
Art Metal Works, Inc., a corporation of New
Jersey

Application March 29, 1935, Serial No. 13,627

8 Claims. (Cl. 67—4.1)

My invention relates to pyrophoric lighting mechanism utilized for any desired purpose such, for example, as the ignition of cigars, cigarettes, pipes, etc., etc.

5 My invention, in an important phase thereof, relates to pyrophoric lighting mechanism constructed and arranged in such manner that a detachable torch member may be utilized in lever or equivalent fashion to actuate the sparking device of said mechanism.

10 Various other objects, advantages and characteristics of my invention will become apparent from the following detailed description.

15 My invention resides in the pyrophoric lighting mechanisms, combinations, features and arrangements of the character hereinafter described and claimed.

20 This application is a continuation in part of my application Serial No. 727,060, filed May 23, 1934.

25 For an understanding of my invention and for an illustration of some of the many forms thereof, reference is to be had to the accompanying drawings, in which:

Figure 1 is a perspective view of pyrophoric lighting mechanism as constructed in accordance with my invention;

30 Fig. 2 is a fragmentary, enlarged vertical sectional view, partly in elevation, of the mechanism shown in Fig. 1;

Fig. 3 is a vertical sectional view, partly in elevation, corresponding generally with Fig. 2 but showing some of the parts in different positions;

35 Fig. 4 is a transverse vertical sectional view, partly in elevation, and is taken on the line 4—4 of Fig. 2 looking in the direction of the arrows;

Fig. 5 is a transverse vertical sectional view, partly in elevation, and is taken on the line 5—5 of Fig. 2 looking in the direction of the arrows;

40 Fig. 6 is a horizontal sectional view, partly in plan, showing a part of the operating mechanism;

Fig. 7 is a vertical sectional view, partly in elevation, showing a modified form of the invention;

45 Fig. 8 is a vertical sectional view, partly in elevation, corresponding generally with Fig. 7 but showing a different relation of some of the parts;

Fig. 9 is a horizontal sectional view, partly in plan, and is taken on the line 9—9 of Fig. 8 looking in the direction of the arrows;

50 Fig. 10 is a fragmentary, transverse vertical sectional view, partly in elevation, of the spark-producing unit;

Fig. 11 is a vertical sectional view, partly in elevation, of a torch member; and

Fig. 12 is a horizontal sectional view, partly in plan, and is taken on the line 12—12 of Fig. 11 looking in the direction of the arrows.

Referring to Figs. 1-6 inclusive, C represents a main casing formed from sheet metal or other suitable material. As herein illustrated, although not necessarily, the main casing C may be open at the bottom thereof so as to telescopically and detachably receive a fuel casing F which, likewise, may be formed from suitable sheet material.

Secured in any suitable manner to the main casing C is a cover plate 1 which, if desired and as herein shown, may be utilized as a support for the various parts of the operating mechanism 15 hereinafter to be described.

At or adjacent the center thereof, the above described cover plate 1 is provided with a circular opening which receives the upper end of a sleeve-like member 2 secured to said cover plate 1 in any suitable manner. In order that the member 2 may thus be secured to the cover plate 1, said member 2 may be provided with a flange 2a which is clamped against the lower cover plate surface by a nut 3 threaded to the extreme upper 20 end of said member 2.

Disposed within the sleeve-like member 2 is a 25 slideable piston-like member or plunger 4 which may have a cap member 5 threaded to the upper end thereof. As shown on the drawings, the cylindrical member 2 may be provided with a pair of diametrically aligned vertically extending slots 2b and the plunger 4 may also be provided with a pair of diametrically aligned vertically extending slots 4b, as illustrated. All of these slots are disposed in aligned relation with respect to each other so as to freely receive a section of a lever 6 pivoted at 7 to a bracket arm 8 depending from the cover plate 1.

A helical spring 9 is disposed within the upper 30 part of the plunger 4, the upper end of said spring 9 engaging the lower surface of the cap member 5 and the lower end of said spring engaging the upper surface of the aforesaid section of the lever 6. The plunger 4 comprises a depending stem section 4c around which is disposed a

35 helical spring 10, the lower end of which rests upon the bottom wall of the cylindrical member 2 and the upper end of which engages the flanged 45 surface 4d of the plunger 4. The stem section 4c is freely slideable in an opening formed in said bottom wall of the cylindrical member 2. Below this bottom wall, the stem section 4c has a 50 washer 11 suitably secured thereto, as by a nut 55

12, this washer 11 comprising an offset section 11a utilizable as hereinafter described.

Secured to the lower end of the member 2 is a ring-shaped bracket 13 having a lever 14 pivoted to a lateral section thereof at 15. As shown in Fig. 3, the lower end of the lever 14 is coactable with the aforesaid washer offset section 11a, the upper end of said lever 14 being notched as indicated at 14a, this notch being adapted to receive the corner of a lug 6a projecting laterally from the aforesaid section of the lever 6. The lever 14 should be biased in a counter-clockwise direction, Fig. 3, either by action of gravity, or by a suitable spring, not shown.

Suitably secured, as by the screws 16, to the upper surface of the cover plate 1 is a housing 17, the opposite vertical walls of which horizontally support a shaft 18. Freely rotatable on the shaft 18 is a sleeve 19 having a gear wheel 20 formed integrally with one end thereof or fixed thereto so as to be movable therewith. Secured to the end of the sleeve 19 opposite the gear wheel 20 is an arm 21 which carries a pawl 22 biased in a clockwise direction, Fig. 3, so that the free end thereof engages a ratchet wheel 23 formed integrally with a sleeve 24 freely rotatable on the aforesaid sleeve 19. Secured to the sleeve 24 for rotatable movement therewith is a wheel 25, the outer peripheral face of which is serrated or roughened for frictional contact with a pyrophoric element 26 which, in part, projects from a tube 27 anchored in fixed position and extending downwardly through the cover plate 1 and the casing C. As well understood in the art, the tube 27 contains a suitable spring, not shown, which biases the pyrophoric element 26 into engagement with the serrated wheel 25.

As illustrated in Figs. 2, 3 and 4, the cover plate 1 is apertured or slotted for the free passage therethrough of the vertical arm of the aforesaid lever 6. As indicated, the upper end of this vertical lever arm is provided with rack teeth disposed in meshing relation with the teeth of the aforesaid gear wheel 20.

As clearly illustrated in Fig. 3, the side of the housing 17 facing the cap member 5 is cut away or apertured as indicated at 17a and, as will readily be understood, this aperture constitutes a passage through which pass the pyrophoric sparks produced when the serrated wheel is rotated with respect to the fixed pyrophoric element 26, these sparks passing above the cap member 5 when it is in its depressed position as shown in Fig. 3.

For a reason hereinafter to be explained, the wall of the housing 17 in which the aforesaid aperture 17a is formed may be of V-shaped configuration as indicated as 17b in Fig. 1.

As shown in Figs. 1 and 2, the cover plate 1 is provided with an opening through which extends the upper end of a tubular member 28 anchored to said cover plate 1 and depending vertically therefrom. This tubular member 28 is vertically aligned with a vertical passage opening into and communicating with the interior of the fuel casing F.

As illustrated on the drawings, the aforesaid tubular member 28 detachably supports a torch member T which comprises a handle 29 having a depending therefrom a tubular member 30 forming a housing for a tubular wick 31 through which a non-flexible core member 32 extends. When the torch T is positioned as shown at the right of Fig. 1, the lower end of the wick 31 is disposed 75 interiorly of the fuel casing F so as to take up

fuel previously charged into the absorbent material 33 contained in said fuel casing F.

Suitably secured to and projecting upwardly from the cover plate 1 is a fulcrum-forming member 34 which may be of suitable configuration such as U-shaped, L-shaped or of the curved configuration shown. In Fig. 2, the various parts of the operating mechanism are shown in normal position. When the mechanism of my invention is to be operated, the torch T is removed from the position shown at the right of Fig. 1 and positioned as shown at the left of said Fig. 1 or as shown in Fig. 2, i. e., with the lower end of the non-flexible core member 32 disposed on the cap member 5 and with the tubular member 30 disposed beneath the lateral section of the member 34. Thereupon, the operator, by manual action, elevates the handle section 29 of the torch T in the direction shown by the arrow in Fig. 1. When the torch T is thus moved, it pivots or fulcrums about the member 34 and the cap member 5 is necessarily depressed in accordance with the upward movement of the torch handle section 29.

The plunger 4 moves downwardly with the cap member 5 and, in response to the downward movement of these parts, the springs 9 and 10 are compressed. During this initial downward movement of the plunger 4, the lever 6 remains stationary by reason of the fact that the lateral pin 6a thereof is in engagement with the notched section 14a of the lever 14.

Eventually, during continued downward movement of the plunger 4, the washer section 11a engages the lower end of the lever 14 to thereby rock said lever 14 in a clockwise direction from the position thereof shown in Fig. 2. As a result, the notched lever end 14a is disengaged from the lateral pin 6a of the lever 6. When disengagement is thus effected, the lateral section of the lever 6, which heretofore has served as a stop surface for the bottom section of the spring 9, is freed from restraint and, accordingly, said spring 9 is permitted to expand suddenly and thereby rock the lever 6 in a counter-clockwise direction from the position shown in Fig. 2 to the position shown in Fig. 3. This action occurs with a snap-action and, in response thereto, a quick step of rotative movement is imparted to the gear wheel 20, the sleeve 19, arm 21, pawl 22, ratchet wheel 23, sleeve 24, and serrated wheel 25, the latter moving in a clockwise direction from the position shown in Fig. 2 with the result that a shower of pyrophoric sparks are produced which pass through the aperture 17a, after the same has been opened as shown in Fig. 3, and come into engagement with the exposed end of the wick 31.

As a result of the foregoing operations, a freely burning flame is produced at the lower end of the torch T. The latter may now readily be removed from its fulcruming position and may quickly be conveyed to any object to be ignited. In so doing, the torch T may be passed about or from hand to hand in order to accomplish any desired lighting operation. After the torch T has served its intended purpose, the flame may be extinguished or, while still flaming, it may be reinserted into the tubular member 28 which serves to snuff the flame. As soon as the torch T has been returned to its normal position as shown in Fig. 1, fuel is again taken up by the lower exposed end of the wick 31.

When the cap member 5 was moved downwardly in response to the fulcruming action of the torch T as described above, the springs 9

and 10 were compressed. When the notched lever section 14a became disengaged from the lateral pin 6a, the spring 9 expanded suddenly, this action being accompanied by further compression of the spring 10.

As soon as the torch T was removed from the cap member 5 as described above, the spring 10 became effective to expand and thereby return the parts to their normal respective positions as shown in Fig. 2. In so doing, the plunger 4 is moved upwardly to elevate the spring 9 and to swing the lever 6 in a clockwise direction from the position shown in Fig. 3 to the position shown in Fig. 2, the lever 6 moving in the direction last noted until the notched lever section 14a again becomes engaged with the lateral pin 6a. When the lever 6 is thus swung in a clockwise direction from the Fig. 3 position thereof to the Fig. 2 position, the gear wheel 20, sleeve 19, arm 21 and pawl 22 idle with respect to the stationary ratchet wheel 23 and stationary serrated wheel 25.

As clearly appears from a consideration of Figs. 2 and 3, the spring 9 is "heavy" while the spring 10 is "light". That is, the spring 9, to a suitable degree, is more resistant to compression than the spring 10. This is a desirable construction because the spring 9 has energy stored therein to produce the pyrophoric sparks in the manner described above.

As shown on the drawings, the apertured wall of housing 17 is of V-shaped configuration. This is desirable because facilitating the act of positioning the torch T in the proper fulcruming position. As will readily be understood, the remote end of the non-flexible core 32 readily slides into the notch of the V and, when thus positioned, is directly above and properly related to the cap member 5.

With the form of my invention hereinbefore described, it will readily be understood that the fulcruming action of the torch produces downward movement of the plunger 4 whereby, as a first act, energy is stored in the spring 9 and, as a second act, a latch is operated to release said spring 9. An arrangement of this character requires the expenditure of a substantial amount of energy and, therefore, it may be desirable to provide a heavy base for the casing C. Or, if desired, the operator may hold the casing with one hand while operating the torch with the other hand. Still further and as illustrated, the cover plate 1 or other suitable part of the casing C may comprise bracket extensions 1b apertured for the reception of fastening screws utilizable for holding the casing C in fixed position. It shall be understood that the arrangement last noted is descriptive only and that any other suitable alternative arrangement may be substituted therefor.

In the form of my invention shown in Figs. 7, 8 and 9, there is provided a main casing C1 which may be associated with a fuel casing F in the same manner as hereinbefore described in connection with Figs. 1-6 inclusive. Suitably secured to the main casing C1 is a cover plate P1 which has a pair of spaced, depending lugs 60, 60a soldered or otherwise suitably secured thereto. Suitably secured to these lugs, as by screws 61 is a depending frame 62 which forms a support for the hereinafter described operating mechanism, said frame, for example, being of generally rectangular configuration as shown in Fig. 9.

Disposed within the shell formed by the frame 62 is a member 63 which extends in generally a vertical direction, the upper end 63a of said

member 63 extending through an opening 64 formed in the cover plate P1. As shown in Figs. 7 and 8, the upper end 63a of said member 63 is provided with a depression 63b, the latter being utilizable as hereinafter described. The member 63 is intended to oscillate in a vertical plane disposed longitudinally of the main casing C1 and, to this end, the lower end of said member 63 may be provided with a pin 63c which seats loosely within an opening formed in the bottom wall of the frame 62. As illustrated on the drawings, the member 63 is biased, for example, by a leaf spring 65 in a clockwise direction, Figs. 7 and 8, said leaf spring 65 being conveniently secured to said lower wall of the frame 62. The member 63 further comprises a pin 63d extending laterally thereof and being utilizable as hereinafter described.

A pin 66, horizontally disposed in the side walls of the frame 62, is adapted to support a lever 67, one horizontal arm of which is notched as indicated at 67a for detachable engagement with the aforesaid lateral pin 63d. The other horizontal arm of the lever 67 is connected by a pin-and-slot connection 68 with the shank sections of a collar 69 which is soldered or otherwise suitably secured to a sleeve 70 mounted for vertical, reciprocal movement in aligned passages formed, respectively, in the bottom wall of the frame 62 and the cover plate P1. As shown in Figs. 7 and 8, a helical spring 71 encircles the lower part of the sleeve 70 and is disposed between the lower wall of said frame 62 and the collar 69, said spring 71 constantly biasing the collar 69 and the sleeve 70 in an upward direction toward a stop member 72 carried by the side walls of said frame 62.

The aforesaid lever 67 comprises a section 67b extending in generally a vertical direction, said lever section 67b terminating on its upper surface in a set of rack teeth 67c. These rack teeth 67c are adapted to mesh with a pinion 73 of a pyrophoric spark-producing unit from which sparks are projected along a path extending above the upper end 63a of the member 63, said pinion 73 being freely rotatable on a pin or axle 74 supported horizontally in a standard 75 upstanding from the cover plate P1. Formed integrally with the pinion 73 is a sleeve 76, the pinion and sleeve being freely rotatable on the axle 74. Freely rotatable on the sleeve 76 is a wheel 77 having a serrated or roughened outer peripheral face. The side of the serrated wheel 77 removed from the pinion 73 is provided with rack teeth 73a with which coacts a ratchet disk 78 mounted on the adjacent end of the sleeve 76, said ratchet disk 78 being biased from right to left, Fig. 10, by a coiled spring 79 which is disposed between said disk 78 and a nut 80 threaded to the outer end of the axle 74. The ratchet disk 78 is freely slidable axially of the projecting end of the sleeve 76 but is otherwise fixed thereto so as to be rotatable therewith. As shown in Figs. 7 and 8, the above described spark-producing unit is enclosed by a cap structure 81 suitably secured to the cover plate P1 and provided with an opening 81a through which the pyrophoric sparks are adapted to pass along the above noted path. As illustrated, the cap structure 81 defines a surface 81b forming a fulcrum to be engaged, in the manner hereinafter described, by the torch member.

The torch member utilizable with the form of my invention shown in Figs. 7, 8 and 9 may be of the character shown in connection with 75

the mechanism illustrated in Figs. 1-6 inclusive. Alternately, if desired, a modified torch member may be utilized with the mechanism illustrated in said Figs. 7, 8 and 9. Thus, as shown in Figs. 5 11 and 12, said alternative torch member may comprise a tubular member 82 terminating in an upper handle section 82a, the lower surface of which defines a flanged surface 82b, Fig. 7. Adapted for association with the member 82 is 10 a member 83 which comprises a shank 83a adapted to be detachably received in the tubular opening at the bottom of said member 82. As shown, the member 83 is of flat configuration and is so shaped as to define a tapered lower section 83b. 15 A wick 84 folded into flat U-configuration axially of the member 83 is secured thereto in any suitable manner, as by the flexible wire 85 which is seated in slots 83c formed at opposite edges of said member 83.

20 It will readily be understood that the ends of the wick 84 are exposed below the lower end of the tubular member 82.

Accordingly, when the torch member is associated with the complete mechanism as shown 25 in Fig. 7, it results that the lower ends of the wick 84 come within the vertical passage defined interiorly of the fuel casing F. As a result, fuel is absorbed by the wick 84 and, since the latter is of substantial length, the supply of fuel which 30 may be taken up by said wick is relatively large.

As the parts are shown in Fig. 7, the lever 67 is in its extreme position in a clockwise direction. The spring 71 is under compression and is so maintained by reason of the fact that the pin 63d 35 of the member 63 is engaged by the notched section 67a of the lever 67.

When the mechanism is to be operated, the handle section 82a of the torch member is grasped to manually remove the same from the 40 tubular member 70 and the tapered section 83b at the lower end of the torch member is positioned in the depression 63b at the upper end of the member 63. Then, in suitable manner, as by utilization of the surface 81b of the cap 45 structure 81 as a fulcrum, the member 63 is moved in a counter-clockwise direction, Fig. 7, to disengage the pin 63d from the notched section 67a of the lever 67. As soon as disengagement of these parts is thus effected, the spring 50 71 is released and expands with a snap action to elevate the collar 69 against the stop surface 72 and to swing the lever 67 in a counter-clockwise direction, Fig. 8. The rack teeth 67c of the lever 67 coact with the pinion 73 and, therefore, 55 a step of movement is imparted to the serrated wheel 77 whereby a shower of pyrophoric sparks are produced, these sparks passing along a path which extends through the opening 81a of the cap structure 81 and igniting the charge of fuel 60 carried by the lower ends of the wick 84.

After the torch member has served its intended 65 ignition purpose, it may again be introduced into the tubular member 70. After the flanged surface 82b thereof engages the upper end of said tubular member, continued downward application of pressure produces downward movement of the tubular member to thereby compress the spring 71 and move the lever 67 from the position shown in Fig. 8 to that shown in Fig. 7. 70 When the lever 67 reaches the position last named, the pin 63d of the member 63 comes into engagement with the notched section 67a of the lever 67 to thereby latch the parts in their 75 respective positions as shown in Fig. 7 so as to

be in condition for subsequent automatic operation in the manner hereinbefore described.

It is to be understood that the mechanisms hereinbefore specifically described are merely illustrative of the many embodiments which the 5 invention may take. Thus, for example, in lieu of the described spark-producing mechanism, it shall be understood that other equivalent arrangements for obtaining uni-directional movement of a serrated wheel may be utilized. Furthermore, it is to be understood that fuel may be supplied to the fuel casing F in any convenient manner. It shall also be understood that the sealing arrangement interiorly of the fuel casings for the lower ends of the respective 15 torch members may assume any one of a variety of forms in accordance with the broad purview of the invention.

It shall be understood that, in one of its broader aspects, my invention relates to the use 20 of a torch as a lever in order to effect operation of the sparking mechanism. In Figs. 1-6 inclusive, the torch-lever, when fulcrumed, energizes a spring and trips a latch in order to effect production of the sparks. In Figs. 7-10 inclusive, 25 the torch-lever, when fulcrumed, merely trips a latch—the spring is energized by a previous action. It will be recognized that two different modes of operation are thus described. However, it shall be understood that the invention 30 is not to be limited to the disclosed modes of operation because, from the broad aspect noted, apparatus of radically different type from that disclosed may be operated by a torch-lever fulcrumed about some fixed part of the lighter 35 casing.

It shall also be understood, as regards the forms of the invention hereinbefore described in detail, that various modifications and changes 40 may be made as desired without affecting the principle of operation in substance.

While the invention has been described with respect to certain particular preferred examples which give satisfactory results, it will be understood by those skilled in the art after understanding the invention, that various changes and modifications may be made without departing from the spirit and scope of the invention and it is intended therefore in the appended claims to cover all such changes and modifications. 50

What is claimed as new and desired to be secured by Letters Patent is:

1. Pyrophoric lighting mechanism comprising a casing, spark-producing means, fulcrum means, an actuating member for said spark-producing means, a spring urging said actuating member toward a position at one limit of its stroke wherein said actuating member is idle, a torch engageable with said fulcrum means and rockable thereabout to depress said actuating member into a 60 position at the opposite limit of its stroke and hold said actuating member in said last named position, and means for transferring energy from said actuating member to said spark-producing means. 65

2. Pyrophoric lighting mechanism comprising a casing, spark-producing means, fulcrum means, a movable member for actuating said spark-producing means, said movable member being positioned between said spark-producing means 70 and said fulcrum means, and a torch engageable with said fulcrum means to actuate said movable member, said torch carrying a charge of fuel positioned in the path of sparks projected from said spark-producing means. 75

3. Pyrophoric lighting mechanism comprising a casing, spark-producing means, fulcrum means, a movable member, a spring intervening between said spark-producing means and said movable member, and a torch engageable with said fulcrum means to actuate said movable member whereby energy is stored in said spring, said torch comprising a wick positioned in the path of sparks projected from said spark-producing means.
4. Pyrophoric lighting mechanism comprising a casing, spark-producing means, fulcrum means, a movable member, a spring intervening between said spark-producing means and said movable member, and a torch having a surface adjacent its lower end adapted to engage said fulcrum means and said lower torch end being adapted to engage said movable member to thereby actuate the same, said torch, when engaged with said fulcrum means as specified, serving to actuate said movable member whereby energy is stored in said spring, said torch comprising a wick positioned in the path of sparks projected from said spark-producing means.
5. Pyrophoric lighting mechanism comprising a casing, spark-producing means, fulcrum means, a movable member for actuating said spark-producing means, and a torch engageable with said fulcrum means to actuate said movable member, said torch carrying a charge of fuel adapted to be positioned in the path of sparks projected from said spark-producing means, said fulcrum means and said movable member cooperating to provide an arrangement whereby said torch is disposed in inclined relation with respect to a horizontal plane when the sparks are projected into engagement therewith.
6. Pyrophoric lighting mechanism comprising a casing, spark-producing means, fulcrum means, a movable member for actuating said spark-producing means, said fulcrum means and said movable member projecting beyond one wall of said casing, and a torch engageable with said fulcrum means to actuate said movable member, said torch carrying a charge of fuel adapted to be positioned in the path of sparks projected from said spark-producing means, said torch being disposed in inclined relation with respect to said casing wall when the sparks are projected into engagement therewith.
7. Pyrophoric lighting mechanism comprising a casing, spark-producing means, a fulcrum member, a movable member for actuating said spark-producing means, said spark-producing means, said fulcrum member and said movable member being positioned above the top wall of said casing, and a torch engageable with said fulcrum member to actuate said movable member, said torch carrying a charge of fuel adapted to be positioned in the path of sparks projected from said spark-producing means, said fulcrum member and said movable member cooperating to provide an arrangement whereby said torch is disposed in an inclined relation above said top wall when the sparks are projected into engagement therewith.
8. Pyrophoric lighting mechanism comprising spark-producing means, a spring, a movable member associated with said spring, fulcrum means, a torch engageable with said fulcrum means so as to actuate said movable member and thereby store energy in said spring, said torch carrying a charge of fuel adapted to be positioned in the path of sparks projected from said spark-producing means, and means whereby the energy stored in said spring is suddenly released to thereby operate said spark-producing means with a snap action.

LOUIS V. ARONSON.
